E. B. AYRES

TOGGLE

Filed April 25, 1924

UNITED STATES PATENT OFFICE.

ELWOOD B. AYRES, OF MELROSE PARK, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

TOGGLE.

Application filed April 25, 1924. Serial No. 709,064.

My invention relates to certain improvements in toggles for attaching leather, or other material, to frames so that a proper drying will be effected.

5 The object of the invention is to simplify the construction of the toggle so that it can be manufactured cheaply, and to design it so that the material to be dried will be held firmly, yet will not come in contact with the supporting frame.

In the accompanying drawings:

Fig. 1 is a perspective view of my improved toggle;

Fig. 2 is a sectional view;

15 Fig. 3 is a side view, showing the clamp in the open position;

Fig. 4 is a side view of the toggle and the supporting frame and leather; in section, the clamp firmly holding the leather;

20 Fig. 5 is a sectional view on the line 5—5, Fig. 2;

Fig. 6 is an enlarged sectional view of part of Fig. 4;

Fig. 7 is a view of the blank forming the 25 body of the toggle before bending; and

Fig. 8 is a view of the blank from which the clamp is formed.

Referring to the drawings, 1 is the body of the toggle and 2 is the clamp. The body is

30 made of sheet metal, of the form shown in Fig. 7. This blank 1^a has lateral projections

3^a, which are perforated at 4 and form the perforated brackets 3 of the toggle. The

blank is punched at 5^a to form a tongue 5,

35 which is bent outwards and is shaped to enter one of the perforations 6 in the supporting frame 7. The frame 7 may be made of perforated metal or of wire netting.

The body blank 1^a is bent on the lines *a*, *b*,

40 *c* and *d*, and is shaped to form a raised gripping surface at one end, as shown in Fig. 2.

Grooves 8 are pressed into the blank, which act to form gripping surfaces for the leather and the pressing of the material to form the

45 grooves produces ribs, which tend to strengthen the toggle at the point where pressure is applied. The two ends of the blank overlap at 9 and may be secured together by welding, or other means.

50 The curved portion 10 of the body is crimped to strengthen the toggle at this point

and to form a neat hand hold used in stretching the leather on the frame.

The clamp 2 is made from a sheet metal blank 2^a, Fig. 8, and has lateral projections 11^a, which form the trunnions 11 of the clamp. These trunnions extend through the perforations in the brackets 3 of the body of the toggle. On the sides of the clamp are stop lugs 12, which limit the opening movement 60 of the clamp, as shown in Fig. 3. The clamp is in the form of a cam and has a portion 13, which bears against the surface of the leather and forces it against the grooved gripping surface 14 of the body. As the leather is 65 pulled, the clamp tightens its hold thereon.

By shaping the toggle in the manner shown, the material being dried is held away from the supporting frame.

I claim:

1. The combination in a toggle, of a body portion composed of sheet metal and comprising a base, a hand hold formed integral with said base at one end thereof, a raised gripping surface formed integral with said base at the opposite end thereof, brackets formed integral with said body portion and respectively located at the opposite sides of said raised gripping surface, and a clamp pivotally mounted in and between said integral brackets and bent to form a cam which is adapted to engage the material and hold it against the said raised gripping surface of the body portion.

2. The combination in a toggle, of a body portion composed of sheet metal bent into tubular form with overlapping edges secured together, said tubular body portion comprising a base, a hand hold formed integral with said base at one end thereof, a raised gripping surface formed integral with said base at the opposite end thereof, brackets formed integral with said body portion intermediate the hand hold and the raised gripping surface and respectively located at the opposite sides of said raised gripping surface, and a clamp pivotally mounted in and between said integral brackets and bent to form a cam which is adapted to engage the material and hold it against the said raised gripping surface of the body portion.

3. The combination in a toggle, of a body portion composed of sheet metal bent into tubular form with overlapping edges secured together, said tubular body portion comprising a base, a hand hold formed integral with said base at one end thereof, a raised gripping surface formed integral with said base at the opposite end thereof, brackets formed integral with said body portion intermediate the hand hold and the raised gripping surface and respectively located at the opposite sides of said raised gripping surface, and a clamp pivotally mounted in and between said integral brackets and bent to form a cam which is adapted to engage the material and hold it against the said raised gripping surface of the body portion.

4. The combination in a toggle, of a body portion composed of sheet metal bent into tubular form with overlapping edges secured together, said tubular body portion comprising a base, a hand hold formed integral with said base at one end thereof, a raised gripping surface formed integral with said base at the opposite end thereof, brackets formed integral with said body portion intermediate the hand hold and the raised gripping surface and respectively located at the opposite sides of said raised gripping surface, and a clamp pivotally mounted in and between said integral brackets and bent to form a cam which is adapted to engage the material and hold it against the said raised gripping surface of the body portion.

5. The combination in a toggle, of a body

portion composed of sheet metal and comprising a base, a hand hold formed integral with said base at one end thereof, a raised flat gripping surface formed integral with said base 5 at the opposite end thereof, said flat gripping surface having a plurality of longitudinally extending grooves formed therein and spaced apart transversely of said flat gripping surface, brackets formed integral with said body 10 portion and respectively located at the opposite sides of said raised gripping surface, and a clamp pivotally mounted in and between said integral brackets and bent to form a cam which is adapted to engage the material and 15 hold it against the said raised flat gripping surface of the body portion, and to force the

said material into the longitudinal grooves formed in said raised flat gripping surface.

4. The combination in a toggle, of a body portion made of sheet metal having a flat 20 base provided with a tongue to extend through a support, said body portion being bent to form a gripping surface on a different plane from the base so as to hold the material some distance from the support; brackets 25 formed integral with the said body portion and projecting on each side of the gripping surface; and a clamp in the form of a cam and pivotally mounted on the brackets and arranged to press the material against the gripping surface of the toggle.

ELWOOD B. AYRES.
